METHOD OF AND APPARATUS FOR TESTING
LOOSE GEOLOGICAL FORMATIONS

Cecil G. Cooley, Chillicothe, Mo.

Application December 16, 1939, Serial No. 309,541

9 Claims. (Cl. 255—1.4)

This application is a continuation in part of, and a substitute for, my co-pending application Serial No. 114,818, filed December 8, 1936.

In the testing of sand and gravel deposits, or other loose geological formations, two methods are in common use. In one, an open well is dug into the deposit to be tested, this method having the disadvantages that piling is necessary if caving occurs and that water, if encountered, must be removed. In the other method, a pipe similar to a well casing is driven into the ground and the materials which come up inside the pipe are periodically bailed out. When the pipe encounters a boulder or other obstruction, it is necessary to interrupt the sampling process and the sinking of the pipe and to break up the boulder by a suitable tool inserted through the pipe.

It is the object of my invention to produce a process and apparatus for sampling gravel, sand, or other loose geological formations and to do so in a manner which will be free from the objections inherent in the prior sampling methods mentioned above. More specifically, it is my object to obtain by an uninterrupted process a continuous sample of loose material in the form of an elongated cylinder and to do so without any substantial disturbance or displacement of the material, whereby it is possible to obtain with a high degree of accuracy information as to the manner in which the character of the material varies with depth.

In carrying out my invention, I drive into the deposit to be tested a suitable pipe or core-barrel (desirably having an internal diameter of at least five inches) provided at its lower end with a tubular cutting element having an annular series of teeth. The pipe or core-barrel is conveniently driven by the use of an ordinary well-drilling rig which imparts a succession of blows to its upper end. In addition to the vertical movement imparted to the core-barrel by the well-drilling rig, I rotate the core-barrel, preferably in timed relation to the frequency of the strokes of the drill rig at a rate which will move the core-barrel through an angle equal to half that between adjacent cutting teeth for each driving stroke of the drill rig. Desirably, the internal diameter of the cutting element at its lower end is made slightly less than the interior diameter of the core-barrel so as to reduce friction and to insure that any material small enough to enter the lower end of the cutting element will not be obstructed in its upward movement relative to the core-barrel. I also prefer to provide the core-barrel with some means which will

tend to prevent the material within it from escaping when the core-barrel is raised.

The core-barrel is driven into the deposit being tested in the manner outlined above. When the cutting element has reached the bottom of the formation to be tested, and not before, the core-barrel is drawn from the ground. During the withdrawal operation the pipe or core-barrel is slowly rotated to reduce static friction and obviate the necessity of jarring the core-barrel and thus disarranging the loose material constituting the core. The material within the core-barrel is elevated with it and represents an accurate cross section of the deposit through which the core-barrel is driven.

The accompanying drawing illustrates my invention: Fig. 1 is a side elevation of a well-drilling rig embodying my invention; Fig. 2 is a vertical section on an enlarged scale through the core-barrel and the means employed to rotate it; Fig. 3 is a top plan view of the barrel-rotating mechanism; and Fig. 4 is a view similar to Fig. 2, but illustrating the upper end of the core-barrel as ready to be drawn from the ground.

The well-drilling rig employed in practicing my invention may take different forms, and that illustrated in the drawing and described herein is to be understood as merely one example. The rig shown is portable in nature, being mounted on an automotive truck 10. In common with most drilling rigs, it embodies a pivoted beam 11 which is oscillated in a vertical plane through the medium of a connecting rod 12 and crank 13. The beam 11 carries two sheaves 14 and 15, mounted respectively near the outer and inner ends of the beam. A cable 18, having one end secured to a winding drum 19, passes therefrom successively around the sheaves 15 and 14 and thence around a sheave 20 at the top of a mast 21. During the process of driving the pipe, the free end of the cable 18 is attached to a driving rod 22 carrying a weight 23. It will be evident from this description that as the crank 13 is rotated the driving rod 22 and its associated weight 23 will be alternately raised and lowered.

A suitable source of power, such as an internal combustion engine 25, is mounted on the truck 10 to drive the crank 13 and other moving parts of the apparatus.

Mounted in rear of the mast 21, I provide a rotating table 27 conveniently supported from a suitable base 28 through an anti-friction bearing 29. The table 27 has an axial hole or opening provided with keyways for the reception of splines on a sleeve 30 adapted to be clamped, as by the

clamp 31, to the drill pipe or core-barrel 32. The sleeve is free to slide vertically in the table 27, but the presence of the splines in the sleeve and the keyways in the table compels the sleeve, and the core-barrel 32, to rotate with the table.

For the lower end of the core-barrel 32 I provide a tubular shoe or cutting element 35 the lower edge of which is formed to provide an annular series of saw-like teeth 36 having downwardly presented cutting edges. At the upper end of the shoe, its internal and external diameters correspond respectively to those of the core-barrel 32. At the lower end of the shoe, however, the bore is made slightly smaller than the internal diameter of the core-barrel, and from its lower end the bore flares upwardly gradually to the internal diameter of the core-barrel. This insures that any object small enough to enter the lower end of the sleeve will not become wedged in the core-barrel and tends to prevent such material from dropping from the core-barrel when it is withdrawn. Moreover, because of the disarrangement incident to the cutting action, the material constituting the core will not infrequently possess a higher proportion of voids than it did in its original state and will thus ordinarily occupy a greater volume; and by constricting slightly the bore of the shoe at the lower end thereof, the amount of material entering the core-barrel is reduced and the core thus prevented from attaining a length materially greater than the depth to which the drill is sunk.

The core-barrel 32 is preferably made up of sections interconnected by screw-thread joints which are flush on both the inner and outer surfaces of the barrel, and the shoe 35 is connected to the lowermost of such sections through a similar joint. I have found it convenient to make the sections of the core-barrel 32 about eight inches in external diameter, about seven inches in internal diameter, and about six feet in length. At the lower end of the shoe the diameter of the bore thereof may be in the neighborhood of six and one-half inches—or about 7% less than the internal diameter of the core-barrel.

The diameter of the core-barrel is of considerable importance for several reasons. There is always a possibility that the shoe will encounter squarely a rock or boulder which is slightly larger in diameter than the bore of the shoe and which might become wedged therein to be driven downwardly into the deposit ahead of the shoe, thus interfering with the cutting action, preventing material from entering the core barrel, and causing an inaccurate sample to be obtained. As the diameter of the core-barrel and of the shoe-bore is increased, the chances of the shoe engaging a boulder of a size to become wedged in the shoe-bore are correspondingly decreased; and moreover, the larger the boulder wedged in the shoe-bore the greater will be the resistance it offers to being driven ahead of the drill and the more effective the drill will be in breaking it up. Again, since my invention is to be used in the sampling of deposits of loose material, such material will always exert considerable pressure on the outside of the core barrel and create friction opposing core-barrel movement. Such friction varies more or less directly as the diameter of the core-barrel; but other things being equal, the strength of the core-barrel will vary as the square of its diameter, and therefore the larger the core-barrel the greater its strength in proportion to the forces which are imposed upon it in operation. In view of these considerations, I

prefer to employ a core-barrel of not less than five inches internal diameter.

For reasons set forth above, the internal diameter of the shoe at its lower end is made slightly smaller than the internal diameter of the core-barrel itself. In practice, it is found expedient to make the bore of the shoe at the lower end thereof about 5% to 10% less than the internal diameter of the core-barrel. If the shoe-bore is 10 materially larger than this, inadequate assurance against jamming of large particles within the core-barrel is provided and the core may tend to climb or to grow longer than the depth to which the core barrel is sunk; and if the shoe-bore is 15 made materially smaller than that indicated as expedient, resistance to progress of the drill is increased and the entrance of material into the core-barrel is restricted to such an extent that the core may have a length materially less than 20 the depth to which the drill has been sunk.

In operation, the drill rig is set up with the table 27 over the spot at which the desired sample is to be taken. The shoe 35 and at least one section of the pipe or core-barrel 32 are connected together and inserted into the sleeve 38 which is then clamped to the pipe. To prevent injury to the threads at the upper end of the pipe, it is desirable to provide a suitable driving cap such as that indicated at 40 in Fig. 2. The 25 driving rod 22 is then inserted into the driving cap and the upper end of the pipe, and the drill rig is started, the winding drum 19 being so adjusted that the weight 23 will strike the driving cap 40 at the lower end of each stroke. The 30 table 27 is operatively connected to the engine 25 to be rotated slowly as the pipe is driven, the table conveniently being formed with an annular series of bevel-gear teeth 42 meshing with a bevel-pinion 43 operatively connected, preferably 35 through a change-speed transmission 44 and a drive chain 45, to some suitable shaft of the drill rig which is rotated, like the crank 13, by power from the engine 25.

As the drill rig operates, the pipe 32 is driven 40 into the ground, while rotating slowly about its own axis as a result of the rotation of the table 27. Ordinarily the table 27 rotates the pipe 32 through an angle equal to about half that between two adjacent teeth 36 for each stroke of 45 the driving rod 22; although rotation at a different relative speed may sometimes be advisable. As the driving of the pipe 32 progresses, additional sections are added to it, the sleeve 38 being transferred to each new section as it is added.

When the pipe has entered the formation to the depth to be tested, the clamp 31 is loosened and the driving rod 22 and driving cap 40 removed. Some means, such as the lifting cap 58 illustrated in Fig. 4, is attached to the upper end 50 of the drill pipe, and an eye 51 in the cap is connected to a hook on the end of a lifting cable 54 which extends over a suitable sheave at the top of the mast 21 and thence to a winding drum or windlass 55. By rotation of the winding drum 55, the pipe 32 is withdrawn from the ground, bringing with it all material which entered it as it was driven. Withdrawal of the pipe is facilitated if it is rotated or oscillated as it is elevated.

To prevent the loss from the lower end of the 60 core-barrel of material which has entered thereinto during the driving operation, I may provide some means tending to retain such material. As illustrated in the drawing, this means takes the form of an annular series of light leaf-springs 61 secured at their lower ends to the inner surface

of the shoe 35. The upper or free ends of the spring strips 60 are bent inwardly of the shoe, as is clear from Fig. 2. The strips 60 afford no material resistance to material entering the shoe from below, as they are easily deflected outwardly against the inner surface of the shoe; but when the pipe is lifted some of any material tending to drop from the shoe will become wedged between the outer surface of the strips 60 and the inner surface of the shoe and will tend to deflect the upper ends of the strips inwardly to form an effective closure for the lower end of the pipe.

I am aware that core-drills, driven entirely by rotation, have been used to sample formations of solid rock as distinguished from the deposits of loose material upon which my machine is intended to operate. A rotating core-drill of that type, however, does not operate satisfactorily in loose material, partly because of excessive friction, partly because the continuous rotation disturbs the material and results in displacements which prevent the obtaining of an accurate sample, and partly because the loose material fills the spaces between the cutting teeth and interferes with their cutting action. My invention has an advantage over the process of intermittent pipe-driving and bailing in that the sample obtained is a continuous one for the entire depth and in that the cutting teeth will cut through any large boulders encountered.

I am also aware that it has been proposed to employ core-drills, driven by combined percussion and rotation, in producing generally horizontal holes in solid rock. It is to be noted, however, that the use of core drills in loose formations of gravel or similar material such as I contemplate, is materially different from the use of core drills in solid rock. For example, in solid rock the drill-shoe cuts clearance for the core-barrel and there is no problem of friction between the core barrel and the material which the drill is penetrating; whereas in loose formations the material closes in behind the shoe and exerts a very considerable opposition to core-barrel movement. Again, in using a core drill in solid rock it is unnecessary to contemplate the possibility that the drill might encounter a loose, hard object which would tend to be driven into the formation ahead of the drill. Still further, a core drill used in solid rock can be withdrawn and reinserted into the hole as desired; whereas such operation is impossible in the drilling of loose material. Moreover, a solid-rock core consists of a single piece or of a comparatively small number of pieces fitting rather closely within the core-barrel, and disarrangement of the core is therefore impossible; whereas to obtain an accurate sample of a loose gravel formation, such as my invention makes possible, it is essential that the drill be so constructed and driven as to minimize the possibility of disarrangement of the particles forming the core. Because of the differences between core-drilling in solid rock and core-drilling in loose formations it is possible, and the general practice, to employ in the former operation core-drills which are materially smaller in diameter than those necessary to secure best results in the practice of my invention.

It will frequently be found advantageous to keep a running record of the level of the top of the core as the pipe is driven. This may be done by interrupting the drilling operation at regular intervals—say intervals of one foot—in the descent of the pipe, and noting the height of

the top of the core. If desired, the drill-rig may be provided with a stroke-counter (not shown) and a record kept of the number of strokes required to drive the pipe through each foot of its descent. Such a record will not only give information during the drilling operation as to the character of the deposit being sampled but will also provide a basis for the elimination of errors which otherwise might arise as the result of vertical displacements of the core during the drilling operation.

Core displacements which might result in error in interpreting the sample can arise from several causes. If the drill is cutting through a stratum of loose gravel having a substantial percentage of voids, some of the gravel in the path of the drill may be displaced laterally and not enter the drill with the result that the whole core will drop. On the other hand, if the drill cuts through a boulder or stratum of solid rock the action of the teeth 36 in disintegrating the formation will result in the creation of voids which will cause the core to be forced upwardly.

After the pipe has been driven and withdrawn from the ground, the several pipe sections are removed and the contents of each examined either as an entirety or in increments. The running record of the height of the top of the core during the drilling operation permits the depth of each core-increment to be accurately determined.

At least to some extent, the displacement of the core relative to the surrounding earth can be reduced by varying the relation between the frequency of the strokes of the drill rig and the speed of rotation of the table 21. Reducing the relative speed of the table tends to lower the core, while increasing it tends to raise the core. In taking advantage of this, I make a continuous observation of the height of the top of the core, as by means of a flexible tape-line 65 provided at its lower end with a small weight 66 adapted to rest on top of the core. The driving cap 40 may have an opening 67 in its wall for the passage of the tape-line.

If, by reading the tape-line 65, it is found that the core is rising relative to the surrounding earth, the variable-speed transmission 44 may be adjusted to reduce the speed of the table. On the other hand, if the core is found to be dropping, the transmission 44 may be adjusted to increase the speed of the table.

I claim as my invention:

55. 1. A machine of the type described, comprising a core barrel, a cutting element attached to the lower end of said core barrel and having an annular series of cutting teeth, mechanism for imparting blows to the upper end of said core barrel to drive it into the ground, and means for rotating said core barrel and operating said mechanism in timed relation, said means being adjustable to vary the speed of pipe-rotation relative to the speed of said blow-imparting mechanism.
60. 2. A process of sampling deposits of sand, gravel, or other loose material which comprises driving a core barrel thereinto by intermittent blows, rotating the core barrel as it is driven, varying the relative speed of core-barrel rotation to maintain approximately constant the level of the top of the core within the barrel, and withdrawing the core barrel and the core it contains.
65. 3. A process of sampling deposits of sand, gravel, or other loose material, which comprises driving a core barrel approximately vertically

thereto by intermittent blows, rotating the core barrel as it is driven, periodically measuring the height of the top of the core of loose material within the barrel, and subsequently withdrawing the core barrel and the loose material it contains.

4. A process of sampling deposits of sand, gravel, or other loose material which comprises driving a pipe forming a core barrel approximately vertically thereto, by intermittent downwardly directed blows, rotating the core barrel as it is driven, continuing the blows and rotation until the desired depth to be tested is attained, anchoring the core of loose material against downward movement relative to the core barrel, removing the core barrel and core from the ground by a vertical movement, and supporting the surrounding loose material upon the exterior surface of the core barrel during the driving and removal of the core barrel.

5. A process of sampling deposits of sand, gravel, or other loose material which comprises driving a pipe forming a core barrel approximately vertically thereto, by intermittent downwardly directed blows, rotating the core barrel as it is driven, continuing the blows and rotation until the desired depth to be tested is attained, anchoring the core of loose material against downward movement relative to the core barrel, removing the core barrel and core from the ground tested by subjecting it simultaneously to an upward pull and to a movement of rotation about its axis, and supporting the surrounding loose material upon the exterior surface of the core barrel during the driving and removal of the core barrel.

6. A process of sampling deposits of sand, gravel, or other loose material which comprises driving a core barrel having an inside diameter of at least five inches into the material in a substantially vertical direction, by subjecting it to rotation and to intermittent downwardly directed blows until the desired depth is attained, whereby the inside of the core barrel will be filled with a core whose geological formation will correspond substantially in position and arrangement with that of the deposit tested, anchoring the core against downward movement in the core barrel, withdrawing the core barrel and its contained core, and supporting the surrounding loose material upon the exterior surface of the core barrel during the driving and removal of the core barrel.

7. A process of sampling deposits of sand, gravel, or other loose material, comprising driving into the deposit by combined rotation and per-

cussion an elongated tubular core-barrel having an open lower end to separate from the remainder of the loose deposit a cylindrical core, continuing the driving of the core-barrel while supporting the surrounding loose material thereby until the desired depth to be tested is attained, whereby to obtain within the core-barrel a core which corresponds in length substantially to the depth of the deposit to be sampled and the geological formation of which corresponds substantially in position and arrangement with that of such deposit, anchoring such core against downward movement relative to the core-barrel, and then simultaneously withdrawing the core-barrel and the core it contains by subjecting the core-barrel to upward pull while rotating it about its axis.

8. A process of sampling deposits of sand, gravel, or other loose material, comprising driving into the deposit by combined rotation and percussion an elongated tubular core-barrel having an open lower end to separate from the remainder of the loose deposit a cylindrical core, continuing the driving of the core-barrel while supporting the surrounding loose material thereby until the desired depth to be tested is attained, whereby to obtain within the core-barrel a core which corresponds in length substantially to the depth of the deposit to be sampled and the geological formation of which corresponds substantially in position and arrangement with that of such deposit, anchoring such core against downward movement relative to the core-barrel, and then simultaneously withdrawing the core-barrel and the core it contains.

9. A process of sampling deposits of sand, gravel, or other loose material, comprising presenting to an exposed face of such deposit the toothed end of a core-barrel having an internal diameter materially greater than the diameter of the particles of which such deposit is formed, rotating the core-barrel while subjecting it to percussion to displace laterally particles in contact with the toothed end of said core-barrel without substantial disintegration of said particles, continuing such rotation and percussion to drive the core-barrel into the deposit to the depth to be tested, anchoring loose material within the core-barrel against relative downward displacement, simultaneously withdrawing the core-barrel and all the loose material which entered its lower end as it was driven, and supporting the surrounding loose material upon the exterior surface of the core barrel during the driving and removal of the core barrel.

CECIL G. COOLEY.
